UNITED STATES PATENT OFFICE

2,146,248

RAILWAY RAIL JOINT

Alfred Nathan Brogden, Blackpool, England

Application November 12, 1936, Serial No. 110,522
In Great Britain December 11, 1935

2 Claims. (Cl. 238—237)

The present invention relates to improvements in rails and rail joints of the type in which the ends of lengths or sections of rail are divided from its centre to be of half-thickness, so that when fitted to a similarly cut rail-end, the two cut parts overlap and form a continuous rail of even thickness.

According to one embodiment of my invention, an end of a rail of half-thickness has a pair of elongated bolt holes alone for the bolts of a two-bolt fish plate or washer plate, the end of half thickness extending beyond the end of the fish plates or washer plates and overlapping a pair of adjacently disposed chairs on supporting sleepers.

Other objects of the invention will be in part obvious and in part pointed out hereinafter.

In order that the invention and its mode of operation may be readily understood by persons skilled in the art, I have in the accompanying drawings and in the detailed following description based thereupon, set out an embodiment of the same.

In the drawings:

Fig. 1 is a diagrammatic view of the use of rails under the invention.

Figure 2 is a plan view.

Figure 3 is a side elevation of the rail joint with the fish plate removed and showing the position of the joint upon the chairs of the adjacent supporting sleepers.

Fig. 4 is a vertical transverse section taken through the rail sections and fish plate at one of the bolt holes showing the clamping bolt for joining the sections.

Figure 5 is a horizontal sectional view through the rail joint.

Figure 6 is a side elevation of the rail joint with a slightly modified form of fish plate applied thereto.

Figure 7 is a horizontal sectional view of the rail joint when employing the fish plates as shown in Figure 6 with parts loosely assembled.

Figure 8 is a vertical sectional view through the same when the joint is tightened and illustrating in dotted lines a flanged rail together with its chair support.

One or both ends of rail lengths 1, 2, are of half width, as shown at 3, 4, respectively, and have their edges preferably bevelled as shown at 5. These half width ends are perforated with holes 6 of standard diameter, but elongated into somewhat elliptical shape as shown, to allow of bolting together of the joints by means of bolts 7 of standard diameter, but allowing for the expansion

of the rails. Washer plates 8 are used as shown.

It is essential to support the joint upon a pair of adjacent sleepers 9—Figure 2—and chairs 10, the rail ends being secured therein by wooden or metal keys.

If desired, the rail ends may be connected by means of standard fish plates cut into halves, and by means of standard bolts, thus affording a considerable saving where these parts are already available. Such a joint is shown in Figures 6 to 9, the standard fish plate being cut into two pieces 11 and having the usual pear-shaped bolt holes 12, co-operating with snugs 13 on the standard bolt 14 to prevent rotation of these.

It will be obvious that by the use of standard fish plate parts 11, as shown, that the joint will be considerably strengthened owing to the support of the fish plates upon the rail ends 3, 4.

It will be obvious that the invention is applicable to any form of rail. A bull-headed rail has been shown purely by way of example; the joint being shown applied to a flat bottomed or flanged rail, in dotted lines at 17, Figure 8.

It will be appreciated that this joint enables shorter bolts to be used if desired, with consequent saving in expense, and it is possible to use a pair of bolts instead of four bolts and two fish plates, as has hitherto been necessary.

It will also be possible to arrange the chairs nearer to one another at the rail ends, thus strengthening the joint. It will be noted from the drawings that the end 5 of each lapping section is spaced away from the opposed end of the cutaway portion so as to provide considerable clearance. This, together with the use of a short washer plate which does not overlap the joint between the sections, and the arrangement of the chairs disposed on opposite sides of the joint, provides a construction which permits expansion and contraction of the rail under rising and lowering temperatures, and which also permits the rails to deflect and react to vibration, not only between adjacent sleepers throughout the length of the rail, but in the region of the joint. The shortened sleeper or washer plate firmly clamps the web sections together and prevents any loosening of the nuts, but does not interfere with deflection of the rails at the joint.

What I claim as my invention and desire to secure by Letters Patent is:—

1. A rail joint comprising rails having the end portions thereof cut away to provide lapping sections, the inner contacting faces of which lie in a central vertical plane containing the longi-

tudinal axis of the rails, non-resilient means for connecting said overlapping end sections including a washer plate disposed between the ends of said lapping sections, elongated bolt holes extending through the washer plate and the lapping sections, and bolts extending through said bolt holes for clamping the washer plate and lapping sections together, the end of each lapping section being sufficiently spaced away longitudinally from the opposed shoulder formed in the other rail by the cutaway portion thereof to permit freedom for vertical deflection at all times.

2. A rail joint comprising rails having the end portions thereof cut away to provide lapping sections, the inner contacting faces of which lie in a central vertical plane containing the longi-

tudinal axis of the rails, non-resilient means for connecting said overlapping end sections including a washer plate disposed between the ends of said lapping sections, two elongated bolt holes only extending through the washer plate and the lapping sections, and bolts extending through said bolt holes for clamping the washer plate and lapping sections together, supporting chairs adjacently disposed on opposite sides of the joint, the ends of the lapping sections extending beyond the washer plate and overlying said chairs, the end of each lapping section being sufficiently spaced away longitudinally from the opposed shoulder formed in the other rail by the cutaway portion thereof to permit freedom for vertical deflection at all times.

ALFRED NATHAN BROGDEN.
